Primary Examiner — Paula Allen Greene(74) *Attorney, Agent, or Firm* — Renner, Otto, Boisselle and Sklar, LLP(57) **CLAIM**

The ornamental design for headphones, as shown and described.

DESCRIPTION

FIG. 1 is a top, front, right perspective view of a first embodiment of headphones showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof;

FIG. 7 is a right side elevation view thereof;

FIG. 8 is a top, front, right perspective view of a second embodiment of headphones showing my new design;

FIG. 9 is a front elevation view thereof;

FIG. 10 is a rear elevation view thereof;

FIG. 11 is a top plan view thereof;

FIG. 12 is a bottom plan view thereof;

FIG. 13 is a left side elevation view thereof; and,

FIG. 14 is a right side elevation view thereof.

The broken lines depict portions of the headphones that form no part of the claimed design.

1 Claim, 14 Drawing Sheets(56)
